UNITED STATES PATENT OFFICE.

REINHOLD SCHMIDT, OF DUSSELDORF-OBERKASSEL, GERMANY, ASSIGNOR TO N. V.
HOLLANDSCHE MAATSCHAPPIJ TOT VERVULGING EN EXPLOITATIE VAN PATE-
TEN EN OCTROEIEN "HOPATEX," OF ROTTERDAM, HOLLAND.

TIME STAMP.

Application filed June 16, 1921. Serial No. 478,104.

To all whom it may concern:

Be it known that I, REINHOLD SCHMIDT, citizen of the German Republic, residing at Dusseldorf-Oberkassel, Germany, have invented certain new and useful Improvements in Time Stamps, of which the following is a specification.

This invention relates to a time-stamp with typewheels which are adjusted with respect to clockwork driven stepped disks by vertically movable slides with abutments or lugs, and more particularly to a time-stamp of this class in which the time stamp proper is separate from the clock-work portion of the stamp and need only be inserted into the clock-work casing in order to be properly adjusted, as described in my prior Patent 1,372,911.

The invention consists in certain improvements in the safety-devices of the time-stamp described in my prior patent to prevent unauthorized use and wrong adjustment and comprises essentially the arrangement of safety-devices upon the hands adjustment and on the coupling between the clock and the gearing, as well as a device for correctly adjusting the hour type upon the stamp, the provision of devices to ensure the smooth introduction of the stamp into the bottom part, in order to effect the damping of the movement, for locking the type wheels in position, as well as safety devices against unauthorized use with wrong time adjustment and against repeated stampings successively, without fresh adjustment of the stamp.

The accompanying drawings illustrate two slightly different forms of the improved time-stamp. In these show:

40 Figs. 1 and 2 the lower portion of one construction in longitudinal section with the parts in different positions.

Fig. 3 is a transverse, vertical section along line A—B of Fig. 2.

45 Fig. 4 a partial longitudinal section in a different plane to Fig. 1.

Fig. 5 a plan corresponding to Fig. 4.

Fig. 6 a transverse section along line C—D of Fig. 4.

50 Fig. 7 a partial transverse section along line E—F of Fig. 4.

Fig. 8 a sectional plan along line G—H of Fig. 7,

Fig. 9 the upper portion of the stamp in longitudinal section along line J—K of 55 Fig. 12,

Fig. 10 a transverse section along line L—M of Fig. 9,

Fig. 11 a partial transverse section along line N—O of Fig. 9, 60

Fig. 12 is a transverse section along line P—Q of Fig. 9,

Fig. 13 a partial transverse-section along line R—S of Fig. 9,

Fig. 14 a longitudinal section along line 65 T—U of Fig. 12 and

Figs. 15 and 16 details in longitudinal and transverse-section.

The other figures show the other form of the improved time-stamp. In these show: 70

Fig. 17 a partial longitudinal section,

Fig. 18 a partial transverse-section,

Fig. 19 the upper stamp in elevation,

Fig. 20 a view of it from below,

Fig. 21 a longitudinal section of the same, 75

Figs. 22 and 23 transverse-sections along lines V—W and X—Y of Fig. 21,

Fig. 24 another longitudinal section along line Z—Z of Fig. 22,

Figs. 25 and 26 partial transverse-sections 80 through Figs. 22 and 23, but with the parts in different positions.

The clock-work 1 is arranged within a suitable casing 2 and drives by the projecting minute shaft 3 a crank-pin 7 of the shaft 85 6 for the stepped-disks 8, 9 and 10. The arrangement and function of these stepped-disks is already known by my prior patent, as is the arrangement of the movable slides 14, 15 and 16 with the abutments or lugs 18 90 and the upward extensions 19, 20 and 21, but the abutment 18 of the slide 16 is in the present case adapted to move laterally, to ensure a safe transmission of the hour figure, as will be described more fully further on. 95

The crank-pin 7 of the improved stamp is axially movable so that it may be coupled with the disk 5 provided with teeth on its circumference and be again detached from 100 it. For this purpose the pin 7 is fixed upon a disk 70, which by means of a spring 71 is usually moved towards the disk 5, said spring being interposed between the disk 70 and a disk 72 fixed upon the shaft 6. Dis- 105 posed within the two front partitions 13

there is a tubular socket 73 within which a plunger 75 controlled by a spring 74 is slidably fitted, said plunger being within the reach of the edge of the disk 70. Above the 5 disk 70 is disposed a double-armed lever 76 fulcrumed at 77, the upper end of which is provided with an inclined plane 78 which extends into the open upper end 22 of the casing 2 of the stamp, into which end the 10 casing 23 of the time-stamp proper is introduced. When introducing the upper casing 23 for the purpose of adjusting the type wheels to the exact time, the lever 76, as clearly shown in Fig. 2, is forced back 15 against the resistance of the spring 79, whereby the forked lower end of the lever 76, the movement of which can be accurately adjusted by means of the set-screw 80, moves the disk 70 so far inwards that the pin 7 20 is withdrawn from the recess 81 of the disk 5, while simultaneously the pin or plunger 75 is forced into one of the recesses 82 of the stepped-disk 8. The recesses 82, which are sixty in number and which, in accordance 25 with the graduation of the said disk 8 for minutes are disposed in a circle, are flared or provided with bevelled edges and follow each other so closely that they touch, so that the pin 75 entering a recess facing 30 or almost facing it locks the stepped-disks 8 or 9 in such a position, that the abutments 18 are always offered a solid contact surface.

By the withdrawal of the pin 7 from the 35 disk 5, the connection between the clock-work and the stepped-disk gearing is entirely interrupted. Hereby the works of the clock are subject to less wear and at the same time the user of the stamp is compelled to withdraw the upper casing immediately after or soon after the introduction in the open end of the lower casing, as otherwise the opening 81 of the disk 5 moves away from the pin 7 under the influence of 40 the clock-work, so that the pin would then not be able to reenter the opening again and a fresh adjustment of the clock would be necessary. In order to allow the disk a little play for the re-introduction of the pin, 45 the edge of the opening is countersunk or bevelled, so that the pin 7 can enter the opening 81 again although the disk has moved forward a little and the pin and hole do no longer exactly coincide. The 50 adjustment of the clock is effected by the button or knob 83 disposed at the back of the casing upon a shaft 84. Upon the other end of the shaft 84 is fixed a pinion 85 which gears with a wheel 86 carried by a lever 87 55 loosely pivoted at its upper end upon the said shaft 84. The lever 87 is furnished at its lower end with an angular piece 88 with which by means of a spring 89 it is drawn against a pin 91 provided with a conical 60 point at its other end and disposed within 65 a guide 90. The pin 91 can be pressed back by the slotted shaft of a key 92 which can be introduced into the casing through an opening 93, the edges of which are strengthened by means of slotted plates 94. These 70 plates 94 only allow the introduction of a suitably shaped key. By pressing back the pin 91 the lever 87 is swung around its fulcrum 84 and the wheel 86 is made to engage the teeth upon the disk 5 whereby the turning 75 of the clock-work by the button 83 is rendered possible. Only the possessor of the special key 92 is therefore in a position to set the clock right.

As already mentioned, the abutment 18 of 80 the slide 16 for the hours step-disk 10 is adapted to be moved laterally to enable it to act at the correct moment of the change from one hour to the next. It has been found that in other apparatus of this kind the passage 85 from the last minute of one hour to the first minute of the next frequently does not take place early enough as in consequence of the slow progress of the hours disk it happens that the tens minutes or units minutes disk 90 indicates the first minute of the next hour while the hours disk still indicates the already passed hour. It is sufficient to cause this wrong indication if the hours step and the corresponding abutment 18 just stand 95 edge to edge.

To avoid this drawback an arrangement has been made by means of which the abutment 18 for the hours stepped-disk is moved a little distance sideways in the direction of 100 the fresh hours step in case the first minute of the fresh hour is adjusted by the tens minutes disk, so that the abutment in its downward movement is pressed upon the correct step with certainty. To attain this 105 result it is necessary to cut out the recessed edge of the stepped-disk 9 for joining with the fifty-ninth minute so deeply, that the abutment 18 for this stepped-disk when located above the recessed edge and being 110 pressed down is moved correspondingly far down. By this deep depression of the abutment 18 of the disk 9 the lateral displacement of the abutment 18 of the disk 10 is caused in the following manner: The abutment 18 for the stepped-disk 10 is not firmly 115 fixed upon its slide 16, like the two other abutments 18, but upon a carriage 95 which by means of pins 96 is guided in slots 97 of the slide 16 (see particularly Fig. 6). The 120 front vertical end of the abutment 18 is situated in a groove 98 of another carriage 99 having guide slots 100 into which projects pins 101 on the corresponding partition 13 (see in particular Fig. 7). This 125 carriage 99 is provided with a roller 102 which engages a curved groove 103 of the slide 15. This groove 103 is so shaped that for a short motion of the abutment 18 for the stepped-disk 9, as owing to the shape of this 130

disk is the case with the minutes figures 10 to 9, the roller 102 remains unaffected, as the groove in the first part of its course is nearly straight. When however, the abutment 18 of the disk 9 passes over the recessed edge of the disk, it will during the introduction of the top casing be pressed so far downwards that the curved groove 103 causes a sidewise motion of the roller 102 with the carriage 99. The carriage 99 hereby also displaces the abutment 18 of the disk 10 which thus during its downward motion comes with certainty in contact with the next stepped-disk. As the deep recess of the disk 9 reaches up to the minutes figure 9, this advance of the abutment for the disk 10 will consequently be caused during the first nine minutes of the fresh hour.

The construction (of the type wheel) for adjustment for the tens minutes indications of the stamp in the upper casing is such that the variable depth of the steps is taken account of by the disk 9. As shown in Figures 9-14 the adjusting device for the type wheels is similar to the construction shown in my prior patent, inasmuch as here also the projections 38 on the lower ends of the slides 35 coming in contact with the extensions 19, 20 and 21 are displaced in correspondence with the position of the stepped-disks, whereby through the agency of the racks 34, the pinions 32 and the pinions 30 and 29, adjustment of the type disks 26, 27 and 28 is effected. The slides 35 are also provided with slots which are guided on bolts 37. The springs 39 for moving the slides into the shown final position are connected, however, in the construction illustrated with the shaft 33 of the wheels 30, 32 and hold these and thereby the type disks in the zero position.

The extension 20 of the slide 15 for the tens minutes disk 9 is longer than the extensions 19 and 21, so that when the stamp or upper casing is introduced the extension 20 will come in contact with the appropriate projection 38 ahead of the extensions 19 and 21, and consequently will cause a sufficient downward motion of the slide 15 with the curved groove 103, when the deep recess of the disk 9 faces the appropriate abutment 18. If on the contrary less deep steps on the disk 9 face the abutment the tens minutes type disk will have a whole idle revolution imparted to it in consequence of the earlier contact of the extension 20 with the projection 38 of the slide 35 for adjusting the tens minutes type disk, whereupon only the adjustment proper of the tens minutes types according to the position of the stepped disk 60 takes place.

The locking of the adjusted type disks is effected, as illustrated, by bell-crank pawls 104 which engage with special ratchet wheels 105 fixed to the type wheels 26, 27 and 28 under the influence of springs 106 which

are fastened to the lateral arms 107 of the pawls 104. The arms 107 abut against the head 108 of the rod 109 which is pulled upwards by means of the spring 43 in the handle 24. The head 108 carries a lateral arm 110 having connected to it a pin 111 which is situated within the path of a double-armed lever 112 disposed at the side of the casing 23. This lever 112 is furnished near its lower end with a square projection 113 which extends outward through a short slot 114 in the wall of casing 23. A spring 115 has the tendency to maintain the lever 112 in the position shown in Fig. 10.

The square projection 113 engages a groove 116 in one side wall of the open end 22 of the lower casing when the stamp or top casing is introduced into the latter and slides in this groove 116 towards the right in consequence of the shape of the groove when the stamp is forced down. Hereby the lever 112 is caused to swing around its fulcrum and pulls the head 108 down through the agency of the pin 111. The head 108 then presses against the arms 107 of the pawls 104 and raises them off the ratchet wheels 105, so that the springs 39 turn the pinions 32 and 30 on the shaft 33, and the pinions 29 and connected type wheels into the zero position. During the further downward motion of the stamp or top casing the square projection 113 under the influence of the spring 115 engages with a tooth-shaped recess 117 of the groove 116, so that a premature withdrawal of the stamp is prevented, while the square projection after completion of the downward motion of the stamp returns into its initial position owing to the shape of the groove 116 and on withdrawal of the stamp rises vertically and thereby raises the guide-pawl 118.

At the bottom 119 of the open end 22 of the clock casing are provided a vertical slotted tube 120 and a vertical pin 121. With the latter a pin 122 of the introduced stamp or top casing comes in contact, said pin 122 being attached to a slide 123 which by means of slots is guided along one of the bolts 37 and another pin 124. A rack 125 at the upper part of the slide 123 gears with a pinion 126 upon a shaft 127, which slide under the influence of a spring 128 is ordinarily maintained in the position shown in the drawing. The shaft is driven through a train of gear wheels connected with two winding wheels 129 and 130 between which a pawl-clutch 132 is intercalated, the ratchet member of said clutch 125 being mounted on a shaft 131.

The slide 123 is furnished with a recess with which engages, in the position shown in Fig. 12, a pawl 134 rotatably mounted upon the bolt 37 and influenced by a spring 130

133 which locks the slide 123 in this position. A cranked lever 135, under the influence of a spring 136, abuts against the pawl 134 and at the same time engages with 5 two pins 137 the toothed wheels 30 for the unit and tens minutes type disks, whereby these are ordinarily locked, so that when the stamp is withdrawn an arbitrary adjustment of the type disks can under no circumstances be effected. A projection 138 upon the pawl 134 with an inclined running up surface meets during the introduction of the stamp or upper casing with the slotted tube 120 upon the bottom plate 119 10 of the open end of the lower casing, whereby the pawl 134 and thereby also the lever 135 with the locking pins 137 are moved out of the way so that the wheels 30 are now free to rotate. During the further descent 15 of the stamp the pin 122 abuts against the pin 121 of the bottom plate 119 whereby the former together with the slide 123 are moved upwardly or inwardly of the stamp. Hereby the pinion 126 together with its 20 shaft 127 are revolved by the rack 125 of the slide 123 and thus the winding wheel 129 is driven through the intermediate wheels 139. Through the resistance caused hereby a desirable and suitable damping of 25 the inserting motion of the stamp is effected, so that the stamp cannot be damaged by clumsy handling. When withdrawing the stamp the spring 128 returns the shaft 127 again to its initial position, whereby also 30 the slide 123 with the pin 122 again projects beyond the bottom plate of the stamp and is again locked in position by the engagement of the pawl 134 with the recess of the slide 123. 35 As the pin 122 in this position prevents the use of the stamp, the person intending to use the stamp must utilize the period of the return movement of the pin 122. The user is thus obliged to press the withdrawn 40 stamp first down upon the ink pad and then immediately upon the article to be stamped. In order that the time at disposal may not be too short, the return of the slide 123 with the pin 122 must be retarded a little. As the winding wheel 129 45 does not suffice for the purpose, the second winding wheel 130 is inserted during the return, which then is driven by the pawl coupling 140 and a further intermediate 50 gearing 141. When a large number of similar imprints are to be made, the pin 122 and the slide 123 can be locked in the withdrawn state. For this purpose a special tubular slit key 55 60 142 is introduced from the outside of casing 23 into the upper end of the slot of the raised slide 123, see Figs. 15 and 16. The hole for this key is protected by means of suitable fittings 143, in a similar manner to 65 the key hole for the key 92 (see Fig. 3.)

The functions of the various safety appliances as well as the manner of adjusting the type disks are briefly as follows:

On the withdrawn stamp ready for making the imprint, the time for which the stamp is set is maintained invariable by the type disks, as the wheels 29, 30 are locked on the one hand by the pawls 104 and on the other hand by the pins 137 on the lever 135. Any further imprint is also rendered impossible by the projecting locked pin 122. When introducing the stamp into the open end of the lower or clock casing for the purpose of setting the type wheels to the correct time for a further imprint, the slotted tube 120 of the bottom plate 119 first strikes the projection 138 on the pawl 134, lifts it and simultaneously moves the pins 137 of the lever 135 out of engagement with wheels 30, so that now when the two pins 121 and 122 75 meet, the latter together with the slide 123 will be moved upwardly or towards the inside, whereby the spring 128 will be subjected to tension and by turning the winding wheel 129 the desired damping or cushioning 80 effect during the introduction of the stamp is obtained. Simultaneously the square pin 113 of the lever 112 which has entered the groove 116 slides along the curve of the groove 116, whereby the lever 112 is moved sideways 85 and by the agency of the pin 111, projection 110 and the head-piece 108 the pawls 107, 104 are raised against the action of the springs 106. Hereby the gear wheels and type disks are set entirely free, so that the springs 39 90 turn the shaft 33 and thereby the slides 35 with the abutments 38, as well as the wheels 30, 32 and 29 with the type disks 26, 27, 28 into the zero position, whereby the guide-slots of the slides 35 form the stop for the 95 final position of these parts. The abutments 38 of the slides 35 which during the further descent of the stamp now meet with the extensions 19, 20 and 21 will then, after the abutments 18 have encountered the stepped 100 disks 8, 9 and 10, be adjusted in accordance with the position of the latter, whereupon after the downward motion of the stamp has come to an end the locking of the adjusted type disks takes place by the pawls 104. The square pin 113 of the lever 112 at 105 the bottom of the groove 116 is pulled back into its initial position in accordance with the shape of the groove, by the spring 115, whereby the head 108 becomes free and the 110 springs 106 immediately pull the pawls 107, 104 against the locking wheels or ratchets 105. After the stamp has been withdrawn the spring 128 by turning the shaft 127 draws the slide 123 with the pin 122 immediately again downwards. As, however, the winding wheels 129 and 130 simultaneously driven hereby retard this motion very much, there is sufficient time for pressing the stamp 115 down upon the inking pad and effecting the 120 125 130

printing. The pin 122, which after the imprint projects to its farthest extent from the bottom plate of the stamp, is now again locked in position by the pawl 134; and by 5 the simultaneously engaged pins 137 of the lever 135, the wheels 30 are also again locked in position, so that an arbitrary setting of the type disks and the further use of the stamp is prevented.

10 Upon the shaft 144 of the type disks 26, 27 and 28 there are disposed besides these time disks special type disks 145 for imprinting the date, which after adjustment are locked by means of a screw-pin 146.

15 The head of the pin 146 is during the introduction of the stamp guided in a longitudinal groove 147 in the open end 22 of the lower casing whereby in conjunction with the square pin 113 and a further pin 148 of 20 the stamp, as well as the corresponding groove 149 of the open end 22, the correct introduction of the stamp or upper casing into the lower or clock casing is insured.

In the modification according to Figs. 17 25 to 26 there is provided instead of the safety pin 122 of the first construction, a spring-actuated projection 150, which after the withdrawal of the stamp from the open end 22 and during the pressing down of the 30 stamp upon the ink pad as well as during the subsequent imprinting is forced back against the resistance of the spring and then locked in position and prevents further imprints being made. A further difference in 35 the construction of the second form of the time stamp relates to the damping device provided in the lower casing of the time- 40 stamp. This device is here so constructed that during the introduction of the stamp its pin 148 meets with a lever 152 fulcrumed at 151 and forces it down against the 45 resistance of a spring 153, whereupon simultaneously a segment 154 drives by counter gearing the winding wheel 155. After the withdrawal of the stamp the spring 153 pulls the 50 lever 152 back into the initial position.

The projection 150 is connected with a bar 55 156 extending into the interior of the stamp casing and with rails 157 and 158 guided within the casing. Springs 159, 160 pressing upon the upper part of these rails endeavour to press the rails and the projection 150 downwards or outwards. The necessary connection is formed by small pins 161 or the like.

The projection 150 is usually locked owing to a lever 163 fixed on a shaft 162 taking up such a position that it is situated just above the bar 156 and thus prevents the bar 60 with the projection from moving upwards (Fig. 23). With the parts in this position the stamp can therefore not be used. Upon the shaft 162 at another place, there is fixed a further short lever 164 which abuts 65 against the upper end of a lever 166, hinged

to the rail 158 at 165, which by a spring 167 is held in the position shown in Fig. 22. Below the shaft 162 a further shaft 168 is disposed, upon which are fixed two segments with ratchet-teeth 169 and 170, against 70 which the levers 163 and 166 abut with a pawl 181 or 182. A spring 171 tends to turn the shaft 168 so that the segments are drawn against the pawls 181 and 182 of the levers 163 and 166. The lever 163 carries at the 75 side a pin 180 against which reposes the arm 172 of a lever 173 rotatably mounted upon the bolt 37 and provided with pins 174 which engage the teeth of the wheels 30 and ordinarily lock them in position, similar to the lever 135 in the first-described construction. One of the pins 174 is engaged by a lever 176 fulcrumed at 175 and controlled by a spring 177. This spring presses the pins 174 into 80 the teeth of the wheels 30 and hereby also 85 the arm 172 of the lever 173 against the pin 180 of the lever 163. The lever 176 is provided with an inclined running-up surface 178 which during the introduction of the stamp meets with the slotted tube 120 90 of the bottom plate 119 in the open end 22 of the lower casing, whereby the lever 176 is pressed back against the resistance of the spring 177, lifting the pins 174 out of the teeth of the wheels 30. Simultaneously the 95 lever 173 with the arm 172 is rotated which by means of the pin 180 and the lever 163 imparts a slight angular motion to the shaft 162 (Fig. 26). Hereby the lever 164 upon the shaft 162 is moved and forces the lever 100 166 back, against the resistance of the spring 167 (Fig. 25). By the movement of the levers 163 and 166 their pawls 181 and 182 recede from the segments 169 and 170, so that the spring 171 is free to rotate the shaft 105 168 so far that the segment 170 is drawn against a pin 179, whereupon the pawls of the segments 169, 170 move past the teeth 181 and 182. After the removal of the stamp from the open end 22, the spring 177 presses the levers 176 and 173 back into the former 110 position, so that the arm 172 recedes from the pin 180. The lever 163 is now in a position in which the projection 150 is at liberty to move inwards.

115 By the double forcing back of the projection 150 by pressing the stamp down on the ink pad and on the article to be imprinted, the lever 163 is again moved back into its initial position, so that it then again locks the projection 150 in position. During the forcing back of the projection, the tooth 182 of the lever 166 passes over the first tooth of the segment 170 and turns it during the rearward movement of the projection with 120 the lever 166 forward by one tooth, whereby the tooth 181 of the lever 163 also engages the first tooth of the segment 169 and the shaft 168 is held in a certain, slightly backward position against the resistance of the 130

spring 171. The second forcing back of the projection (the imprinting) causes the lever 166 with its tooth 182 to pass over the second tooth of the segment 170 and to carry it along during the inward motion of the projection. In consequence the segment 169 is turned so far that the tooth 181 of the lever 163 slides behind the second tooth of the segment 169 and thus again comes into its locked position with regard to the bar 156. A further pressing back of the projection 150 is now prevented and only possible after the release of the lever 163 by the introduction of the stamp into the open end 22 of the clock casing.

The projection 150 may be provided with an appliance which forces the user to apply the stamp to the ink pad, as otherwise an indication becomes visible which shows that the ink pad has not been used.

It is obvious that the construction and arrangement of the mechanism described may be variously modified within the ambit of the claims without departing from the spirit of the invention.

What I claim as my invention and desire to secure by United States Letters Patent is:

1. In a time-stamp, the combination with a clock, a casing therefor, setting disks, gearing for the setting disks, and a stamp, of means to prevent unauthorized use and wrong adjustment of the stamp comprising: safety devices upon the hand setting arrangement of the clock and upon the coupling between the clock and the gearing and an appliance for correctly adjusting the hours, means for ensuring the smooth introduction of the stamp into the casing, type disks, means for locking the type disks, means for preventing the use of the stamp with wrong time adjustment and several times in succession without fresh adjustment, means for automatically returning the type disks to zero, means for allowing the making of a large number of similar imprints, and means for making special date imprints.

2. In a time-stamp of the class described, the combination with a clock, a casing therefor and a stamp, of means for disconnecting the clock and the gearing for the stepped disks when the stamp is introduced into the casing.

3. In a time-stamp of the class described, the combination with a clock, a casing therefor and a stamp, of means for disconnecting the clock and the gearing for the stepped disks when the stamp is introduced into the casing, and means for locking said gearing to the casing.

4. In a time-stamp of the class described, the combination with a clock, a casing therefor and a stamp, of means for detachably connecting the clock and the stepped disks, which comprise an axially movable crank-

pin adapted to engage and be disengaged from a countersunk hole in the toothed disk upon the minutes shaft.

5. In a time-stamp of the class described, the combination with a casing, and a set of stepped disks therein, of means for detachably connecting the stepped disks and the casing which comprise an axially movable spring-controlled pin adapted to engage an annular series of countersunk openings provided in the first step-disk, said openings touching one another with their outer peripheries.

6. In a time-stamp of the class described, the combination with a clock and a toothed disk associated therewith, of a safety-key for winding up the clock, a lever adapted to be swung sideways by the introduction of the key in the key-hole, and a setting train adapted to be thrown into gear with the toothed disk of the clock consequent upon such movement of said lever.

7. In a time-stamp of the class described, the combination of a set of stepped disks and a laterally movable abutment for the hours stepped disk, the lateral movement being adapted to take place in the direction of the succeeding hours disk when the gear changes to the following hour, substantially as and for the purpose described.

8. In a time-stamp of the class described, the combination of a set of disks, a slide for each disk, a laterally movable abutment for the hours disk, a special carriage for supporting said abutment, and a second carriage provided with a groove for guiding said abutment, said second carriage being adapted to control said abutment in such a manner that the lateral movement of the abutment takes place when the slide of the tens minutes disk which indicates and adjusts the first minute is pressed down.

9. In a time-stamp of the class described, the combination of a stamp, a set of stepped disks, a slide for each disk, an abutment and an extension for each slide, and a carriage for the abutment of the hours disk, the extension upon the slide for the tens minutes disk being of such dimensions that it meets the projections of the descending stamp earlier than the remaining extensions, said tens minutes disk having a recess which is situated so low between the last minute figure up to the ninth minutes figure, that when the said extension is depressed into the deep recess of the disk the carriage with the abutment for the hours disk is displaced laterally in the direction of the step for the following hour.

10. In a time-stamp of the class described, the combination of a stamp, a set of stepped disks, a slide for each disk, an abutment and an extension for each slide, and a set of type disks in said stamp, the extension upon the slide for the tens minutes disk being higher

than the other extensions, so that the adjustment of the corresponding type disk in the stamp is effected during the introduction of the stamp by the contact of the abutment with

5 the shallower steps of the tens minutes disk in such a manner that the type disk performs a complete idle revolution before the adjustment proper takes place.

11. In a time-stamp of the class described, 10 means for automatically locking the type disks of the stamp after their adjustment in position by means of pawls, comprising a lever engaging during the introduction of the stamp a curved groove in the open end of the lower casing by means of a pin and a head-piece in such a manner, that the type disks are first released and after adjustment locked in position.

12. In a time-stamp of the class described, 20 a casing, type disks therein, locking pawls normally holding said type disks against rotation, means for automatically releasing said pawls consequent upon the introduction of the stamp into the open end of the casing, 25 and controlling springs for the disks to automatically return them to the zero position when such release takes place.

13. In a time-stamp of the class described, 30 the combination of a clock, a casing therefor, a stamp, and means to prevent the already used stamp from being used again before being again introduced into the open end of the clock casing, said means comprising an element projecting beyond the 35 bottom plate of the stamp and being locked in that position.

14. In a time-stamp of the class described, 40 the combination of a casing, a stamp adapted to be inserted therein, and means for damping the insertion of the stamp into the casing comprising a slide provided with a pin, a winding wheel, a gearing connecting the slide with the winding wheel, and a pin projecting from the bottom plate of 45 the open end of said casing which meets with the said pin on the slide and by which it is pressed back after the release of the locking device.

15. In a time-stamp of the class described, 50 means for preventing an arbitrary adjustment of the type disks, comprising gear wheels for transmitting the adjustment to the type disks which after the adjustment of the disks and the withdrawal of the 55 stamp from the lower casing are locked in position by means of locking pins on a spring-controlled lever.

16. In a time-stamp of the class described, 60 upper and lower casings, and a slotted tube upon the bottom plate of the open end of the lower casing, the said tube entering the upper casing during its downward movement and throwing a lever with locking pins

out of engagement, as well as a pawl, and thus releasing the slide for the pin of the 65 damping device.

17. In a time-stamp of the class described, 70 a stopping pin, and means for retarding the motion of the stopping pin and its locking in place in order to give sufficient time for pressing the stamp down on the ink-pad and to effect the imprint, said means comprising a winding wheel, a second winding wheel, and a counter gearing for driving the second winding wheel from the first one. 75

18. In a time-stamp of the class described, 80 means for allowing repeated similar imprints, comprising a protective pin normally preventing repeated imprints, and a special key which holds said protective pin in its inactive position.

19. In a time-stamp of the class described, 85 the combination of time-printing disks, a shaft whereon they are mounted, special type disks for printing the date adjustably mounted upon the shaft of the time-printing disks and adjacent to them and a set screw for locking said special disks in adjusted position.

20. In a time-stamp of the class described, 90 a member guided within the stamp and projecting below its bottom plate, such member after the setting of the type disks allowing the stamp to be pressed down twice, once for inking and once for imprinting, whereupon 95 it is locked in position and prevents the further use of the stamp.

21. In a time-stamp of the class described, 100 a member in the bottom plate of the stamp, said member being locked in its projecting position by means of a pawl which is thrown out of engagement by a lever through the agency of a slotted tube upon the bottom of the open end in the lower part of the stamp during the introduction of the 105 stamp, while the pawl is returned to the locking position by two successive depressions of the member through the agency of a lever and two toothed segments.

22. In a time-stamp of the class described, 110 a projecting member movably fitted in the bottom plate of the stamp, said member being provided with an indication which becomes visible when the stamp has not been pressed down upon the ink-pad. 115

23. In a time-stamp of the class described, 120 the combination of a stamp, a casing, a clock therein, a winding wheel, a gear train connected with the winding wheel for damping the introducing movement of the stamp into the open end of the casing, said gear train being disposed upon the bottom part of the stamp and being adapted to be operated by an abutment pin upon the stamp.

In testimony whereof I affix my signature. 125
REINHOLD SCHMIDT.
